UPRIGHT LAUNDRY RECEPTACLE

Olive M. Thomas, New Buffalo, Mich.

Application April 4, 1935, Serial No. 14,677

3 Claims. (Cl. 150—49)

This invention relates to an upright laundry receptacle, the general object of the invention being to provide a collapsible frame having a laundry bag removably connected to its upper end and a second bag for clothes pins or the like removably connected to a side portion at the upper end of the frame so that one can take articles from the bags and place articles in the bags without stooping and by having the bags removably connected with the stand or frame they can be readily removed for laundry and like purposes and by having the stand or frame collapsible it can be readily carried from place to place and will occupy but little room when stored.

This invention also consists in certain other features of construction and in the combination and arrangement of several parts, to be herein-after fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a perspective view of the invention in operative position.

Figure 2 is a similar view with the parts in folded position.

Figure 3 is a perspective view of the stand or frame with the bags removed.

Figure 4 is a perspective view of the laundry bag.

Figure 5 is a perspective view of one corner portion of the clothes pin bag.

Figure 6 is a view of a corner portion of the laundry bag.

Figure 7 is a view of the double hook plate.

Figure 8 is a view of the single hook plate.

In these drawings the letter A indicates the frame or stand which is composed of the two pairs of legs 1 and 2, the legs of each pair being connected together by the cross pieces 3 with the central piece 3' acting to pivotally connect together the legs intermediate their ends. A plate 4 is fastened by two screws or the like to the inner face of the upper end of each outer leg 1 and this plate has a hook 5 formed at its outer end. A longer plate 6 is fastened by two screws or the like to the outer face of the upper end of each inner leg 2 and this plate 6 has a hook 7 at each end thereof shown more particularly in Figure 7.

The laundry bag is shown at B and may be formed of canvas or any other suitable material and is substantially of rectangular shape and has

an opening 8 at the upper part of each corner thereof, the material adjacent these openings being gradually turned back as shown at 9 and I prefer to connect the four corners of the bag by French seaming 10, the top part of which holds in place the bottom end of each two of the graduated turnbacks. A hem 11 is formed around the upper edge of the bag and the seams forming the hem hold in place the top ends of the turnbacks. This manner of holding top and bottom of the turnbacks makes a neat finish without the necessity of stitching down the turnbacks. The hem 11 receives at each of the four corners a strap 12, these straps extending between each pair of turnbacks and act as means for suspending the laundry bag from the hooks 5 on the plates 4 and the inner hooks 7 of the plates 6. When the straps are inserted between the pairs of turnbacks the turnbacks are pulled slightly together, thus lessening the distance around the top of the laundry bag and pulling the frame work up to a neat and attractive angle without lessening the capacity of the laundry bag.

As it will be seen it is simply necessary to insert the straps 12 into the hooks to attach the laundry bag to the top of the frame and to pull the straps from the hooks when the bag is to be removed from the frame. The bag is formed of a single piece of material sewn together at the corners, there being no seams at the bottom.

The clothes pin bag is shown at C and is composed of the front and rear pieces of canvas or any other suitable material, the two pieces being of like dimensions at the bottom and lower corners but the underpiece is gradually narrowed horizontally toward the top. When the two are sewn together this gives a flare of approximately two inches to the outside piece 14, making it stand open and easier to reach into. The side edges of the bag slope slightly upward and inwardly. I prefer to sew this pin bag together with a French seam with the second sewing on the outside to make a neat appearance. At each of the two upper corners a loop forming strap 15 is sewn in with the French seam and these loops are used to suspend the bag from the outer hooks 7 of the plates 6.

Some of the many advantages of this invention are that it is upright and it is not necessary for the user to stoop to place the clothes in the basket nor stoop to remove the clothes from the basket either in ironing or in hanging the clothes up on the line. The invention is easily movable and can be carried about in the wash room as well as out of doors. It can be used for holding the

clothes after they are dampened ready for ironing. Another very important advantage is that there is no projection upon which clothing can be caught or torn as there is on the ordinary clothes hamper or clothes basket. Another advantage is that when the receptacle is carried it partially collapses, making it easier to carry it through doors or narrow places and that it will stand partially open and partially closed. When not in use it can be folded and stored away in a small place or can be suspended from one of the cross rods. Both of the bags are easily removed and easily laundered. All metal parts are rust-proof. The laundry bag is so hung that there is plenty of room to grasp the cross member so that the receptacle can be carried.

It is thought from the foregoing description that the advantages and novel features of the invention will be readily apparent.

20 It is to be understood that changes may be made in the construction and in the combination and arrangement of the several parts, provided that such changes fall within the scope of the appended claims.

25 What is claimed is:—

1. A device of the class described comprising a foldable upright frame including two pairs of legs pivotally connected together intermediate their ends, means for connecting the legs of each pair together, inwardly extending hooks at the

upper ends of the frame, a fabric bag having openings at the upper portions of its corners, and straps extending across the openings and connected with the bag and detachably engaging the hooks.

5

2. A device of the class described comprising a foldable upright frame including two pairs of legs pivotally connected together intermediate their ends, means for connecting the legs of each pair together, inwardly extending hooks at the upper ends of the frame, a fabric bag having openings at the upper portions of its corners, and an angle-shaped flexible part extending across the upper part of each opening and connected with the upper edge of the bag and detachably engaging the hooks.

3. A device of the class described comprising an upright collapsible frame formed of two pairs of legs pivotally connected together intermediate their ends, cross pieces connecting the legs of each pair together, plates connected to the upper ends of the legs, one pair of plates being connected to the inner faces of the outer pair of legs and having hooks at their inner ends, the other pair of plates being connected to the outer faces of the inner pair of legs and having hooks at their inner ends, a fabric bag having openings in the upper portions of its corners, and a strap extending across each opening for engaging the hooks.
